United States Patent Office.

JOHN STOCK, OF EL PASO, ILLINOIS.

Letters Patent No. 67,816, dated August 13, 1867.

IMPROVED BUREAU AND BEDSTEAD.

The Schedule referred to in these Letters Patent and making part of the same.

TO ALL WHOM IT MAY CONCERN:

Be it known that I, JOHN STOCK, of El Paso, in the county of Woodford, and State of Illinois, have invented a new and "Improved Combined Bureau and Bedstead;" and I do hereby declare that the following is a full, clear, and exact description thereof, which will enable those skilled in the art to make and use the same, reference being had to the accompanying drawings, forming part of this specification.

The present invention consists in constructing a box or case, which, upon its exterior has all the appearance of an ordinary bureau, in such a manner, and in parts hinged or hung together, that they can be opened from each other and brought into a horizontal position for use as an ordinary bedstead, while, at the same time, if so desired, they can be brought into an upright position and shut the one upon the other, forming a bureau to all outward appearances, with the mattresses and other articles constituting the bedding encased within the same. In the accompanying plate of drawings my improved combined bureau and bedstead is illustrated—

Figure 1 being an elevation of one end to the same when in a bureau or box form, and

Figure 2 a central longitudinal vertical section with the parts in position for use as a bedstead.

Similar letters of reference indicate corresponding parts.

A, in the drawings, represents my improved combined bureau and bedstead constructed as follows: B, the bottom board supported and standing upon a flange, C, that forms the base thereto. This bottom B has, at each end, a raised piece, D, that, when the bureau is opened, forms a part of the sides to the bedstead. To both the front and back edges of the bottom board B are hinged a board, E and F, respectively, that, in connection with the end pieces G and H thereto, and side pieces I and J properly formed and shaped that, when the parts are hung up into a vertical position, a box or case will be formed, externally will have all the appearance of a bureau, while, when in a horizontal position, a bedstead will be formed. To hold the several parts together when in a vertical position, hooks L are provided.

I claim as new, and desire to secure by Letters Patent—

The combined bureau and bedstead, constructed as described, consisting of the bottom B, having raised pieces D hinged to the boards E F, having end pieces G and side pieces I adapted to form a bedstead when opened, and a bureau when folded up, as herein shown and described.

JOHN STOCK.
